TIMING APPARATUS

William R. Hewlett, Palo Alto, and David Packard, Los Altos, Calif., assignors to M. P. H. Industries, Palo Alto, Calif., a corporation of California

Application October 24, 1949, Serial No. 123,255

8 Claims. (Cl. 161—1)

1

This invention relates generally to timing apparatus such as is useful for producing one or more responses in predetermined timed relation to an actuating signal.

In the past various types of timing devices have been used for securing one or more responses in predetermined timed relation to receipt of a controlling signal. For example it has been proposed to employ a simple type of electrically energized perforating device which serves to apply perforations in a continuously moving paper tape. The tape in turn moves continuously past one or more sets of electrical contacts which are operated according to the positioning of the perforations. The rate of movement of the tape and the spacing between the perforating device and the contacts serves to determine the time interval between receipt of a signal and operation of the contacts. Another type of timing device is shown in Marihart 2,437,168, in which a plurality of mechanical lugs are frictionally retained upon the periphery of a wheel, and are released by receipt of a signal to move with the periphery of the wheel. One or more switches are placed in the path of movement of the lug whereby they operate at predetermined intervals following the release of the lug.

Timing devices of the type described above, and other devices which are available for this purpose, are subject to a number of disadvantages. In particular they have been complicated with respect to the mechanical elements employed, and they have been subject to inaccuracies in the timing provided. In addition they have not been well adapted for high speed operation.

It is an object of the present invention to provide novel timing apparatus which will utilize a minimum of mechanical parts, and which will make possible delayed timing to a high degree of accuracy.

Another object of the invention is to provide timing apparatus of the above character which can operate at relatively high speeds, and which when so operated is not subject to serious mechanical deterioration.

Another object of the invention is to provide apparatus of the above character in conjunction with novel circuit means characterized by provision for continuing energization of a magnetizing device after receipt of a signal, and for automatically rearming the circuit means.

Additional objects of the invention will appear from the following description in which the preferred embodiments have been set forth in detail in conjunction with the accompanying drawing.

2

Referring to the drawing:

Figure 1 is a diagrammatic view illustrating the present invention, and incorporating circuit means of the relay type.

5 Figure 2 is a view like Figure 1 but illustrating a modification of the invention in which the circuit means includes electronic amplifiers.

Figure 3 is a view like Figure 1 but illustrating another embodiment of the invention in which a 10 special type of electronic circuit means is employed.

Figure 4 is a diagrammatic view like Figure 1, but illustrating another embodiment of the invention which incorporates the electronic means 15 of Figure 3, together with additional automatic means for insuring rearming of the circuit.

Figure 5 illustrates another circuit which can be employed to perform the essential functions of the circuit shown in Figure 4.

20 Figure 6 is a side elevational view showing suitable mechanical details for a portion of the invention.

In general the present invention employs a 25 movable member formed of magnetizable material, in conjunction with an electromagnetic device which is adapted to be energized to effect local magnetization of the member, and one or more electromagnetic pickup devices. The rate of movement of the magnetizable member, together with the spacing between the electromagnetic devices, determines the time interval between receipt of a signal to cause a magnetizing effect, and receipt of a response by the electromagnetic pickup means.

35 Referring first to Figure 1 of the drawing, we have shown a magnetizable member 10 which is 40 movable at a continuous speed and which for example may be in the form of an endless tape, drum, or disc. It is of such construction that it

can be magnetized in a localized area with retention of such local magnetization until magnetically erased. It is satisfactory to use relatively thin carbon steel, as for example sheet steel ranging from say 0.003 to 0.006 inch in thickness, or

45 we may employ surface coating of magnetizable material, such as finely divided magnetizable material, applied to a base material which is non-magnetic. As diagrammatically illustrated in Figure 1 it is assumed that the member 10 is the 50 peripheral margin of a disc or wheel.

At one point along the path of movement of the member 10 there is an electromagnetic device 11, which is adapted when energized to effect local magnetization of the member 10. Electromagnetic pickup devices 12 and 13 are also shown, and

beyond the pickup device 13, there is a magnetic eradicating device 14. Device 14 can be placed a short distance in advance of the electromagnetic device 11.

Each of the devices 11, 12 and 13 are diagrammatically illustrated as including a magnetic core, together with a winding. The pole pieces of the cores are arranged in close proximity with one side of the member 10. Eradicating device 14 can be a simple permanent magnet, or an electromagnet continuously excited with alternating current.

In the embodiment of Figure 1 circuit means of the relay type is used in conjunction with the electromagnetic device 11, and the pickup device 12. Thus the circuit means includes a relay 16 having two sets of contacts 1 and 2, and the two windings 3 and 4. The winding 4 connects with an input circuit 17, upon which a signal or actuating pulse is applied. The winding 3 is included in a holding circuit 18, which includes the contacts 2, the contacts 5 of a relay 19, and the battery or source of current 20. The contacts 1 are included in an energizing circuit 21 for the device 11, and which includes the battery 22 or other source of current. Contacts 1 and 2 are normally opened, while contacts 5 are normally closed.

Assuming that current is applied to the winding 4 of the relay 16, contacts 1 and 2 are closed to energize the device 11. The closing of holding contacts 2 closes the holding circuit 18, so that thereafter both contacts 1 and 2 remain closed, irrespective of discontinuance of current applied to the winding 4. The circuit is now disabled in that it will not respond to receipt of another signal, until rearmed. Energization of the electromagnetic device 11 causes creation of an intense localized magnetic field, the flux path of which includes a portion of the member 10, whereby a localized area of this member is permanently magnetized. Assuming that the member 10 moves at a constant speed, while the device 11 continues to be energized, the magnetization will continue for an extended area until device 11 is de-energized. As the advancing end of the magnetized area passes the electromagnetic pickup device 12, a current is induced in the winding of the same which energizes relay 19 to open the contacts 5. This serves to open the holding circuit 18, thus de-energizing winding 3, and permitting the contacts 1 and 2 of the relay 16 to open. Thus the device 11 is de-energized and the circuit is rearmed or reset, and now is in condition to respond to a new signal applied to the circuit 17.

The pickup device 13 has its winding connected to the input of an amplifier 23, the output of which is connected to a device 24 to be operated, such as a solenoid. In place of amplifier 23 we may employ a suitable relay circuit.

When the advancing end of the magnetized area passes the electromagnetic pickup device 13, the current induced in the winding of this device is supplied to the amplifier 23, to provide amplified output current for operating the device 24. Device 24 may be any suitable mechanism operated by a current pulse and serving to perform any one of various operations.

It will be evident that the time interval between application of a signal to circuit 17, and receipt of the response by device 24, will be a predetermined value dependent upon the rate of movement of the member 10, and the distance between devices 11 and 13.

When the magnetized area passes the magnet

14, it is erased, thus eliminating magnetization before being returned to the electromagnetic device 11.

In Figure 2 we have illustrated circuit means employing electronic amplifiers, in place of the relay type of circuit illustrated in Figure 1. Thus the signal circuit 26 is shown connected to the input of amplifier 27 and the output of this amplifier connects with the winding of electromagnetic device 11. The signal is also shown being applied to the electronic time delay means 29, which in turn is likewise connected to amplifier 27. Amplifier 27 is preferably of the type which must be restored for normal operation, after being tripped by application of a signal. The time delay means 29 is designed to supply such a restoring pulse a predetermined time interval after amplifier 27 has been operated by a signal.

The electromagnetic pickup device 12 in Figure 2 is shown connected to the input of amplifier 28, and the output of this amplifier is likewise connected to apply a restoring pulse to the amplifier 27, for normal resetting or rearming in the manner described with reference to Figure 1.

With the arrangement of Figure 2 it is presumed that after application of a signal, amplifier 27 energizes the electromagnetic device 11 and continues such energization until a restoring pulse is applied. Normally the restoring pulse is applied when the advancing end of the magnetized area passes the electromagnetic pickup device 12. If for some reason this restoring pulse is not applied, then such a pulse is automatically applied by the means 29. It will be evident that this arrangement facilitates use in applications where the speed of movement of the member 10 is synchronized with some other mechanism, as for example the forward speed of movement of an agricultural machine of the type disclosed and claimed in Marihart application Serial No. 707,439 filed November 2, 1946. Assuming use with such a machine the current from amplifier 23 can be used to operate the clutch solenoid for effecting timed operation of the ground engaging cutters, and the signal applied to circuit 26 can be obtained from the photoelectric tube and amplifier means which is operated by light responses received from growing plants. Normally the time interval between energization of device 11 and the restoring of this device, will be dependent upon the speed of forward movement of the vehicle, which in turn determines the speed of movement of member 10. However if device 12 together with amplifier 28 fails to effect restoration of the amplifier 27, then within a fixed time interval following energization of device 11, the system is automatically rearmed.

Figure 3 illustrates a special type of circuit for controlling energization of device 11. Thus in this case two tubes 31 and 32 of the thyratron type have their cathodes 33 connected together, and to one side of the output of amplifier 34. The control grid 36 for tube 31 is connected to the other side of the output from amplifier 34, through the condenser 37. The control grid 36 for tube 32 is connected to one side of the winding of electromagnetic pickup device 12, and the other side of this winding connects with the cathodes 33. A biasing battery 38 or other source of negative biasing voltage is shown connected in series with grid 36, and the grid of tube 31 is connected to a source of negative bias through the resistor 39. The indicated source of anode current is connected between resistors 41 and 42. Resistor 41 connects with the anode 43 of the

tube 31 in series with the winding of device 11, and resistor 42 connects directly with the anode of tube 32. Condenser 45 connects across the resistors 41 and 42.

The circuit of Figure 3 operates to energize the device 11 responsive to application of a signal to the input 44 of the amplifier 34, and is restored by operation of the pickup device 12. Normally the tube 31 is nonconductive, and tube 32 is conductive. The grid 36 of tube 31 is normally negatively biased. Condenser 45 is charged because of the potential difference applied to the same. Upon application of a signal to the input of amplifier 34, the grid of tube 31 is driven positive whereby the tube 31 is made conductive to cause current flow through the winding of device 11. At the same time tube 32 is made nonconductive because condenser 45 momentarily causes the anode of the same to assume a potential negative relative to the cathode. The circuit is now disabled in that it will not respond to application of another signal. Tube 31 remains conductive until actuation of the electromagnetic pickup device 12. Current induced in the winding of device 12 places a positive potential upon the grid of tube 32 with the result that this tube is fired and becomes conductive, and whereby because of the action of condenser 45, tube 31 is extinguished. Thus device 11 is de-energized by actuation of the pickup device 12 and the circuit is rearmed to respond to the next signal.

The circuit illustrated in Figure 4 is similar to that of Figure 3, except that additional automatic means is employed for restoring the circuit after a predetermined period of time, and irrespective of operation of device 12. Thus in this instance a condenser 46 is connected between the cathodes 33, and each cathode is connected to the grounded side of the output of amplifier 34, through resistors 47.

Assuming that tube 31 is extinguished, and tube 32 conducting, condenser 46 is charged by virtue of the voltage across that resistor 47 which is connected to the cathode of tube 32. When the tube 31 is made conductive by a signal applied to circuit 44, and the tube 32 made nonconductive, condenser 46 starts to discharge through the resistors 47. The size of the condenser 46, and the values of the resistors 47, are selected so that condenser 46 is substantially completely discharged after a predetermined time interval. This time interval is selected so that it is somewhat longer in duration than the average time interval intervening between energization of device 11, and responsive operation of the pickup device 12. When the condenser 46 looses its charge the tube 32 is fired and the tube 31 is extinguished. Thus the circuit is automatically rearmed.

It will be evident that the circuit arrangement of Figure 4 can be used to insure rearming of the circuit irrespective of whether or not the pickup device 12 is properly actuated.

The circuit illustrated in Figure 5 is a monostable type Eccles-Jordan multivibrator and makes use of triodes 51 and 52 or other suitable type of vacuum tube. The anode 53 of tube 51 is connected to the indicated source of plate current in series with the resistor 54 and the winding of device 11. The plate 53 of tube 52 is connected to the source of plate current through the resistor 56. The grid 57 of tube 51 is connected to one side of the output of amplifier 34 in series with the rectifier 58. The cathode 59 of tube 51 is grounded and connected to the grid 75

of tube 51 through resistor 61. Also a battery or other source of biasing voltage 62 is shown connected in series with the resistor 63 and across the output of amplifier 34.

The grid 57 of tube 52 is connected to the plate of tube 51 by resistor 64 and is also connected to ground through the resistor 65. One side of the winding of device 12 connects with the grounded side of the network and the other side connects through the coupling condenser 66 and rectifier 67, with the grid of tube 52. The cathode of tube 52 is grounded as indicated. A battery 68 or other source of biasing voltage is connected in series with the resistor 69, and from ground with the point of connection between condenser 66 and rectifier 67. Condenser 71 is connected between the grid of tube 51 and the plate of tube 52.

To explain operation of the circuit illustrated in Figure 5 it will be presumed that tube 51 is normally nonconductive while tube 52 is conductive. Assuming application of a signal to the circuit 44, the amplified signal component drives the grid of tube 51 from negative to positive, thus making this tube conductive to energize the winding of device 1. At the time this tube is made conductive the grid of tube 52 becomes negative with respect to the cathode of this tube such that the tube becomes nonconductive. Immediately prior to receiving an actuating signal the condenser 71 is charged by virtue of the voltage difference applied to the same. When tube 51 becomes conductive and tube 52 nonconductive, due to application of a signal, condenser 71 starts to discharge.

When current is induced in the winding of device 12 by passage of the advancing end of the magnetized area, the grid of tube 52 is driven toward positive to make this tube conductive and the grid of tube 51 is in effect driven toward negative to render the same nonconductive.

The capacity of condenser 71 is such that normally it is not fully discharged by the time the circuit is rearmed by actuation of pickup device 12. If the pickup device fails to properly rearm the network then complete discharge of condenser 71 occurs with the result that the grid of tube 51 is made negative to thereby automatically make the tube 51 nonconductive, and tube 52 conductive.

Figure 6 schematically illustrates a mechanical device which can be used in connection with the invention. In this instance the member 10 is in the form of a thin flat disc made of suitable carbon steel. The magnetic devices 11 and 14 are shown supported by an arm 12 which is carried by the fixed support 13. The devices 12 and 13 are mounted upon the arms 14 and 15 which can be angularly adjusted as indicated. While the arms 14 and 15 are in this instance shown mounted upon the same side of the disc 10, it should be understood that they can be mounted upon opposite sides to thereby increase the latitude of adjustment. The disc 10 is mounted upon a rotatable shaft 76 which can be driven from any suitable mechanism. As previously pointed out, the disc can be driven at a constant rate, or at a rate which may be varied from time to time as in the aforementioned Marihart agricultural machine.

In place of member 10 being in the form of a disc as illustrated in Figure 6 it will be evident that it may be in the form of an endless band, tape or drum.

We claim:

1. In timing apparatus, a continuously movable member of magnetizable material, an electromagnetic device located along the path of movement of said member and adapted when energized to effect a localized magnetization of said member, circuit means for effecting energization of said electrical magnetic means, electromagnetic pickup means likewise located along the path of movement of said member and spaced from said first named electromagnetic device, said electromagnetic pickup means being responsive to passage of a localized magnetized region of said member, and means actuated by a response from said electromagnetic pickup means for insuring rearming of said first named circuit means.

2. In timing apparatus, an endless movable member of magnetizable material, an electromagnetic device located along the path of movement of said member and adapted when energized to effect localized magnetization of said member, circuit means responsive to a signal for effecting energization of said electromagnetic device, said circuit means being disabled to respond to subsequent signals until rearmed, an electromagnetic pickup device located along the path of movement of said member and spaced from said first named electromagnetic device, said electromagnetic pickup device being responsive to passage of a localized magnetized region past the same, and means connecting said electromagnetic pickup device to first named circuit means and serving to rearm first named circuit means responsive to actuation of said electromagnetic pickup device.

3. Timing apparatus as in claim 2 together with another electromagnetic pickup device located along the path of movement of said member, and responsive to movement of a localized magnetized portion of said member past the same, and magnetic means located in advance of said first named electromagnetic device for eradicating residual magnetization of said member before a portion of the same moves past said electromagnetic device.

4. In timing apparatus, an endless movable member of magnetizable material, an electromagnetic device located along the path of movement of said member and adapted when energized to effect localized magnetization of said member, an electronic network responsive to a signal for effecting energization of said electromagnetic device, said circuit serving to continue energization of said device after application of a signal and until application of a rearming pulse, an electromagnetic pickup device located along the path of movement of said member and spaced from said first named electromagnetic device, said pickup device being responsive to passage of a localized magnetized region past the same, and circuit means connecting said pickup device to said first named circuit means whereby an induced current pulse from said pickup device causes rearming of said electronic circuit means.

5. Timing apparatus as in claim 4 together

with an additional electromagnetic pickup device located along the path of movement of said member and responsive to passage of a localized magnetized region past the same, and response means connected to said last named pickup device.

6. Timing apparatus as in claim 4 together with means incorporated in said electronic circuit to automatically restore the same after a predetermined time interval following application of a signal.

7. In timing apparatus, an endless movable member of magnetizable material, an electromagnetic device located along the path of movement of said members and adapted when energized to effect localized magnetization of said member, an electronic network responsive to a signal for effecting energization of said electromagnetic device, said circuit serving to continue energization of said device after application of a signal and until rearming of the same, an electromagnetic pickup device located along the path of movement of said member and spaced from said first named electromagnetic device, said pickup device being responsive to passage of a localized magnetized region past the same, response means operatively connected to said pickup device, and means for automatically rearming said electronic circuit after a predetermined time interval following application of a signal.

8. In timing apparatus, an endless movable member of magnetizable material, an electromagnetic device located along the path of movement of said member and adapted when energized to effect localized magnetization of said member, an electronic network responsive to a signal for effecting energization of said electromagnetic device, said circuit serving to continue energization of said device after application of a signal and until rearming of the same, an electromagnetic pickup device located along the path of movement of said member and spaced from said first named electromagnetic device, said pickup device being responsive to passage of a localized magnetized region past the same, response means operatively connected to said pickup device, and means for automatically rearming said electronic circuit after an interval following energization of the first named electromagnetic device but before energization of the second named pickup device.
